COVER FOR THE BED OF A PICKUP TRUCK

James C. Havens, 13062 Red Hill Ave., Tustin, Calif.

Filed July 28, 1959, Ser. No. 56,966

Term of patent 14 years

(Cl. D14—6)

Figures 6, 7 and 8 are fragmentary sectional views taken respectively on lines 6—6, 7—7 and 8—8 of Figure 1; and

The dominant features of the cover reside in the portions shown in solid lines. The undisclosed side is a mirror image of the one shown in Figure 3.

I claim:

The ornamental design for a cover for the bed of a pickup truck, substantially as shown and described.
